UNITED STATES PATENT OFFICE

2,489,415

COMBINATION SILL AND AIR DUCT

Juanita M. Hyde, Tampa, Fla.

Application July 1, 1946, Serial No. 680,726

2 Claims. (Cl. 98—88)

1

This invention relates to a ventilating means for buildings, and more particularly to a combination sill and air duct, adapted to admit fresh air into a room in an upward direction inwardly of a window sash or door, so as to pass upward over the inner surface of the window sash or door and avoid drafts against occupants of a room such as occurs by opening windows or providing openings through a wall leading directly into a room, and providing for the displacement of foul air and supply of fresh air to replace same.

Another object of the invention is to provide a combination sill and ventilator or air duct by which the volume of air entering a building or room may be controlled, without interfering with the provision of a flat supporting surface at the inside of the sill, the air entering from under a projecting outer portion of the sill, so as to eliminate the entrance of rainwater or dust settling thereon, and by screening said opening at the inlet, under the sill, eliminating the hazards from vermin, mosquitoes, snakes, flies, etc.

Another object of the invention is to provide a sill having a hollow chamber with a projecting outer ledge and a bottom member, together with a controlled damper in the inner portion of the sill on the inside of the window sash or door, to control the volume of air entering and to direct the same upwardly for efficient ventilation, and also providing means for allowing of the entrance of makeup air downwardly to a point near the floor, in ventilating a room, either by cooling or heating the same under the action of forced ventilation in causing the circulation of air as a cooling or heating medium, and rendering the same under control at all times.

Another object of the invention is to admit the air at the inside and bottom of a window sash or door, so as to counteract heat radiation at its source, to provide more effective cooling comfort, as well as healthier living conditions and greater heating efficiency, with complete freedom from drafts at less cost than possible with systems requiring air ducts using individual wall openings or openings placed at the sides, top or bottom of the window or door openings, and allowing the air to enter in a path clear of the occupants of the room or rooms, in the occupancy areas, with greater velocities and smaller ducts than where the air spills into the room with the resultant draft hazards of high velocity, and requiring but one minimum size opening properly placed at the window frame, as well as providing a stronger wall construction due to the necessity of but one air entrance opening serving both for sill, win-

2

dow and duct, as well as permitting screening thereof to exclude insects and dirt, undisturbed in case of blackouts, and proper control of the supply of fresh makeup air for the heating system delivered at the most efficient point without additional cost or additional openings in the outer wall of the room or building without marring or interfering with the outside or inside appearance of the sill or building wall from the presently accepted designs.

Other objects and advantages reside in the details of construction and operation as more fully hereinafter described and claimed, reference being had to the accompanying drawings forming part hereof, wherein like reference numerals refer to like parts throughout, and in which—

Figure 1 is an outside elevation showing the invention applied to a wall opening of a building represented as a window opening, although capable of application to any form of wall opening, whether a window louver or a door.

Figure 2 is a fragmentary elevation taken on the plane of the line 2—2 of Figure 1 looking upwardly.

Figure 3 is a vertical sectional view taken on the line 3—3 of Figure 1.

Figure 4 is a fragmentary inside elevation showing the invention applied and partly broken away, and

Figure 5 is a fragmentary horizontal sectional plan view with the combination sill and air duct applied as in the other figures.

Referring to the drawings in detail, in which like reference characters designate corresponding parts throughout the several views, 10 designates a suitable wall of any desired construction, such as building block, frame, concrete, or tile 11, with mortar joints 12, and arranged upon a suitable foundation. An opening 13 is provided in the wall, and may be a window, louver, or a door opening, with an upper wall structure 14 above the same. As shown, the opening is provided with a frame 15 including frame sides, of which the portion 14 may form a top member or header, while a bottom member 16 also forms the bottom of a sill 17, and may be of wood, plastic, or metal, as desired. The window or door is designated at 18, and may be a sash frame, with a suitable panel, such as 19, of glass or otherwise. While the window may be fixed, so as not to move or open, it is to be understood that the window or door may be slidable, or hinged to swing horizontally or vertically to open or close, and of course, in the case of a door, obviously the same would be mounted on vertical hinges to swing

horizontally. Obviously, either the window, louver or door may be considered as a closure in a wall opening, irrespective of the opening and closing feature thereof. The sill 17 is formed of sheet metal or other material of suitable character, and forms a hollow chamber therein over and with the bottom member 16, shaped to provide an inner horizontal sill portion adapted to be closed by a damper plate or louver 20. The sill proper has a vertical portion or stop 21 and is extended inwardly horizontally, as indicated at 22, to form an adjustable support for the damper or louver 20. From the depending shoulder or stop 21, the outer sill 23 slopes downwardly in an outward direction and overhangs the wall 10, in spaced relation to the outer surface of the latter with a depending portion 24 terminating in an inwardly extending shoulder or flange 25 at the bottom edge thereof in spaced relation to the front of the wall at the bottom member 16 of the sill which forms a chamber 26 between the same and the top member of the sill. A suitable open grid, consisting of foraminous material or wire screen 27 is supported upon the flange 25 and may be secured thereto, as indicated at 27', at its outer edge so as to extend inwardly horizontally and then in front of the bottom member 16, as indicated at 28, where it may be secured by a horizontal strip or face plate 29, as indicated at 30, or by other suitable means. Any number of vertical strength-giving members in the form of stiffeners, spacers or partitions 31 may be provided in the chamber 26 between the bottom member 16 and the top portion of the sill 17 so as to give support thereto. As shown, the damper plate or louver 20 is provided with a depending arcuate ratchet or other suitable member 39 contacting a fixed lug 40 and manipulated by a gripping portion or head 41 at the top, so as to adjust the angle of inclination and degree of opening thereof according to the quantity of air which it is desired to admit through the circuit or path up through the screen 27 and then inwardly and upwardly through the opening at the inner side of the sill in the manner clearly shown by the arrows in Figure 3 of the drawings. Also, the air may pass downwardly through the space 32 between outer wall member 10 and inner wall member 33 by providing an opening 42 in the latter in which is set a rotatable or other damper 43 of any desirable construction, shown having a perforated plate or spider 44 over which the plate 43 is rotatably mounted, as indicated at 45, and provided with a handle or knob by which the plate may be turned so that the entrance of fresh air may be provided at or near the floor for use in makeup purposes when using a heating system. This is in direct contrast to the entrance of fresh air through openings provided in the wall, or by opening the window or door, to cause drafts against the occupants of the room, which is entirely eliminated by the present invention.

It will thus be seen that I have provided a very desirable combination sill and air duct, and by forming the sill in the manner described, of hollow construction, the necessary strength is provided to support the window sash or door threshold to rest thereon, as well as to form the top of the air duct in connection with the bottom member forming the internal chamber 26 through which air is admitted to the room through the screened opening at the projected outer portion or ledge of the sill extending outwardly from the outer face of the wall structure 10 of the building.

The design of the air duct is such that outside

air for summer cooling is drawn through it by means of a fan via a weather-protected, screened inlet, opening to and through a damper or louver properly controlling the outlet, so that by placing the same inside of the window or door within the room, the entering air travels inwardly and upwardly over the sun-exposed surface of the window or door, so as to counteract heat radiation at the source. Also, the air enters the room in an upward direction deflected by the inclined damper, which forms a baffle and directs the air upwardly inside of the window and along the same, as well as toward the top of a room to prevent drafts on the occupants which result from openings extending directly into a room horizontally, or by opening a window or door. Also, by opening the ventilator 42, the air may pass downwardly through the vent or space 32 from the chamber 26 through an opening in member 16, as indicated at 49, communicating with the space 32, as shown in Figure 3 of the drawings, so as to permit the entrance of outside air required for makeup purposes for winter heating, flowing by fan-induced suction through the sill, then downward and through the air space separating the outer and inner building walls and into the room at or near the floor level, where it diffuses with the heated air circulation. It should also be noted that the damper for controlling the volume of incoming, cooling air is made up as a hinged shelf, which, in closed position, forms part of the inner member of the sill at the top, and, in a raised position, acts as a deflector to force the path of the incoming air against the window or door glass and upwardly into the room; which provides more effective cooling comfort, healthier living conditions, and complete freedom from drafts at less cost than possible with systems requiring air ducts using individual wall openings or openings placed at the sides, top, or bottom of the window or door openings. Also, since the air travels in a path clear of the occupants of the room, greater velocities and smaller ducts are permissible than where the air entering the room spills directly into the room with the resultant draft hazards with high velocities. Thus, it is possible to use a smaller size entrance opening for the air, the opening being of minimum size and properly placed in the window or door sill, so that a stronger wall construction is obtained due to one opening serving for both window opening and duct. The screened inlet opening under the sill eliminates passage of vermin, mosquitoes, snakes and flies, and prevents the entrance of rainwater, dust and dirt, etc. Also, the outside appearance is not changed from the present accepted designs.

While in the foregoing there has been shown and described the preferred embodiment of this invention, it is to be understood that minor changes in the details of construction and combination and arrangement of parts may be resorted to without departing from the spirit and scope of the invention as claimed.

Elimination of balanced or hinged sash with protective screens and required hardware assures a material saving in the low-cost housing program presently sponsored by the Federal Government.

What I claim is:

1. In combination with a building wall having an opening for a closure and composed of an outer wall member and an inner wall member extending above said outer wall member, a closure frame fitted in said opening and including side and bottom frame members, a sill comprising a single sheet extending from side to side of the

lower portion of the frame over and in spaced relation to the bottom frame member, said sheet being shaped to provide a horizontal inner edge portion spaced from the inner wall member, an outwardly inclined portion projecting outwardly beyond the outer wall member, a vertical closure stop portion connecting said inner edge and inclined portions, and a depending outer edge portion terminating in an inwardly extending bottom flange spaced from the outer edge of said bottom frame member, a horizontal grid connecting said bottom flange to the outer edge of said bottom frame member and spanning the space between said bottom flange and said bottom frame member, an adjustable damper plate hinged to the inner wall member and spanning the space between the upper edge of said inner wall member and the inner edge portion of said sheet, and vertical partitions between said sheet and said bottom frame member.

2. The construction defined in claim 1, wherein

said inner wall member is spaced from the outer wall member and has an opening below and in a vertical plane between the ends of said sill, and a damper set in the last-named opening.

JUANITA M. HYDE.
